UNITED STATES PATENT OFFICE

FRANK AUGUSTUS WARDWELL, OF METHUEN, MASSACHUSETTS.

CANE-GUN.

SPECIFICATION forming part of Letters Patent No. 349,864, dated September 28, 1886.

Application filed March 24, 1886. Serial No. 196,333. (No model.)

To all whom it may concern:

Be it known that I, FRANK AUGUSTUS WARDWELL, of Methuen, in the county of Essex, of the Commonwealth of Massachusetts, have invented a new and useful Improvement 5 in Cane-Guns; and I do hereby declare the same to be described in the following specification and represented in the accompanying drawings, of which—

10 Figures 1 and 2 are longitudinal sections of the handle and the next adjacent part of the barrel of a "cane-gun" containing my invention, the nature of which is defined in the claims hereinafter presented. Fig. 3 is a longitudinal section of the handle on the line 1 1 of Fig. 1. Fig. 4 is a side view of the handle, showing part of it broken away in order to exhibit certain portions of the lock.

15 In Fig. 1 the breech-piece is shown as up or covering the breech of the charge-chamber, while in Fig. 2 such breech-piece is shown as down, so as to uncover the said breech in order to admit of a cartridge being inserted in such chamber.

20 In the said drawings, A represents the barrel, which is screwed upon a screw, a, extending from the stationary part B of the handle, the bore b of the barrel being in continuation of a cartridge-receiving chamber, b', arranged with 25 in the handle part B and its screw a, such chamber being open at its rear end, and there rabbeted to receive the flange or head of the cartridge-shell. There is applied to the rear face of the handle part B the sliding breech-piece C, which at its upper part is notched, as 30 shown at c in Fig. 4, to receive a correspondingly-shaped projection or shoulder, d, from the part B when the breech-piece is up and covering the breech or rear end of the cartridge-chamber b'. The breech-piece C is connected to the handle part B in a manner to enable such breech-piece to be moved or slid 35 downwardly upon the said part B. To this end there are two slots, g, in the said handle part B. Screws e go through these slots and washers f and screw into the part C, the heads of the screws being sunk within the washers. In the upper part of the breech-piece there is a bolt, f', which is provided with a spring, h, 40 to force it forward into a notch, i, in the han-

45 dle part B. Such bolt has a lever, k, for re-tracting it, the said lever having its lower arm projecting through the breech-piece, in manner as represented in Fig. 1. By pressing inwardly the said lower arm by the thumb, 55 when a person may be grasping the handle, the bolt may be retracted to enable the breech-piece to be moved downwardly upon the handle part B. The breech-piece has extending upward from its upper end a tenon, l, to enter a recess or mortise, m, in the projecting part d of the handle portion B, such tenon and mortise or recess being to hold the breech-piece firmly in place against the back-pressure of the cartridge-shell during an explosion of 60 the charge or load thereof. Both portions B and C of the handle are chambered to receive the parts of the lock now to be described. The hammer is shown at D and its operative spring at E, such hammer being within and 65 pivoted to the breech-piece C. The tail n of the hammer extends through a slot, o, in the part B, and is notched, as shown at p, to receive the upper arm of a catch-lever, q, in order to hold the hammer cocked. A spring, r, 70 bears against the lower arm of the lever q, as shown in Fig. 1. The trigger is represented at s as a lever borne against the tail of the catch-lever q by a spring, t, arranged as represented in Fig. 1. The trigger, at its upper 75 end or part, projects through the handle part B, as shown at u. By bearing against the part u by the index-finger the catch-lever will be forced out of engagement with the hammer when the latter is cocked. There is within 80 the part B a projection or shoulder, v, against which the tail of the hammer is forced while the breech-piece is being moved downwardly to uncover the cartridge-chamber. In this movement of the breech-piece the hammer will 85 be cocked, and will remain cocked while the part C is being moved upward to close the charge-chamber. There is within the part B a cartridge-extractor, it being shown at G in Fig. 1 as a slide adapted to extend up into the 90 charge-chamber and to slide longitudinally thereof. It is jointed or applied to the upper end of a lever, H, whose longer or lower arm is curved, as shown in Figs. 1 and 4. While the part C is being slid downward a cam or 95 100

stud, *w*, projecting from one of the washers *f*, is moved against the said arm, and thereby turns the lever and operates the cartridge-extractor, so as to cause it to expel the spent cartridge-shell from the charge-chamber. On forcing a fresh cartridge into the charge-chamber the extractor will be moved back thereby to place; or it may be so moved by the wedge-shaped tenon at the top of the part *C* while such part *C* is being forced upward; or the part *G* or its lever *H* may have a retractive spring applied to them to effect the return movement of the extractor.

I claim—

- 15 1. The combination of the barrel *A* and the handle part *B*, extending therefrom, with the movable or sliding breech-piece *C*, connected to and fitted to slide on such part *B*, and forming therewith the handle of the cane-gun, the 20 hammer and its catch-lever and their operative springs, carried by such breech-piece, and the trigger and its actuating-spring applied to the said part *B*, such hammer having its tail extending within the said part *B*, and the latter being provided with the projection *v*, and all being arranged and to operate substantially as set forth.
- 25 2. The combination of the barrel and the handle part *B*, connected therewith, and hav-

ing the recessed projection *d*, with the movable or sliding breech-piece *C*, provided with the tenon to enter the said projection, and connected with and fitted to slide on such part *B*, and forming therewith the handle of the cane-gun, such part *C* being provided with the lock-hammer, its actuating-spring, and catch-lever and its actuating-spring, and the part *B* being furnished with the trigger and its actuating-spring, and the projection against which the tail of the hammer, extending within such part *B*, strikes in order to effect the cocking of the hammer, as specified.

3. The combination of the barrel *A* and its handle part *B*, extending therefrom, with the movable or sliding breech-piece *C*, connected to and fitted to slide on such part *B*, and forming therewith the handle of the cane-gun, the hammer and its catch-lever and their operative springs, carried by such breech-piece, and the trigger and its actuating-spring, and the cartridge-extractor and its operative lever applied to the part *B*, all being substantially and to operate as set forth.

FRANK AUGUSTUS WARDWELL.
